UNITED STATES PATENT OFFICE.

IRVING M. STEIN, OF LONG BRANCH, NEW JERSEY, ASSIGNOR TO THOMAS E. MURRAY,
OF NEW YORK, N. Y.

APPARATUS FOR LIMITING THE TRACTION OF AN ELECTROMAGNET.

1,189,883.

Specification of Letters Patent.

Patented July 4, 1916.

Application filed November 17, 1915. Serial No. 61,906.

To all whom it may concern:

Be it known that I, IRVING M. STEIN, a citizen of the United States, residing at Long Branch, in the county of Monmouth and State of New Jersey, have invented a certain new and useful Improvement in Apparatus for Limiting the Traction of an Electromagnet, of which the following is a specification.

10 The invention is an apparatus for limiting the traction of an electro-magnet. The principle thereof consists in first saturating the magnet core and then confining the excess flux to a circuit wherein it can exert 15 practically no torque on the armature. Said principle may be embodied in many forms of apparatus, of which I here show one which I have found to be operative and useful, and which is a relay of the watt-meter 20 type. Induction instruments when subjected to heavy overloads or short-circuits vibrate or rattle violently. This impairs the accuracy of the apparatus and sometimes injures it. Inasmuch as watt-meter relays 25 come into operation when said overloads or short circuits take place, they are especially subject to the above difficulty, and therefore I have chosen such an instrument for illustration herein.

30 In the accompanying drawings, Figure 1 is a front elevation and Fig. 2 a side elevation of the working parts of a watt-meter relay embodying my invention. Fig. 3 is a plan view of the armature and circuit closing connections, and Fig. 4 is a perspective view of the series coils, core therefor and a part of the armature—designed more particularly to show the flux paths hereinafter described.

40 Similar letters and numbers of reference indicate like parts.

The electro-magnet A has a bifurcated laminated core B. A portion 1 of said core at the ends of the arms thereof is turned at 45 substantially a right angle to the remaining or body portion 2 thereof. The series coils C are applied to the portion 2. The part 1 of the core is substantially perpendicular to the rotary armature D, and the 50 part 2 substantially parallel thereto. The armature D is placed, as usual, in the instrument between the series coils C and the potential coil E which is carried by core F. The armature spindle G carries an arm H 55 which enters a yoke I on the end of a flexi-

ble arm J, to which is secured one lead K of the relay circuit. The other lead L is connected to an arm M which carries a contact N, wherewith a contact on arm J operates when the armature D has been rotated a predetermined distance, thus establishing the relay circuit.

In watt-meter relays as ordinarily constructed, the core of the series coil is in the shape of an inverted U with both legs straight and disposed at right angles to the face of the armature which is placed very near to the polar ends. The field of the magnet is, therefore, placed so as to produce maximum torque on the armature. The iron in this series magnetic circuit becomes saturated after a certain current value is reached; but the current in the coils continues to increase the field since there is no opportunity for the flux to leak or, in other words, to take any path other than through the armature. Consequently the vibration or rattling of the parts before noted occurs.

Referring to Fig. 4, when the coils C are energized the flux circuit, indicated by the 80 light arrows at 3, proceeds through both arms of the core and cuts the armature. This flux I cause to continue until the core becomes saturated. The excess flux is then due to the coils C only. By reason of the 85 placing of the coils on the part 2 of the core, the path or circuit of this excess flux, indicated by the heavy arrows 4 in Fig. 4, becomes parallel to the plane of the armature D, and hence will exercise no torque 90 thereon. In other words, after first causing the iron core to become saturated, I cause the excess or leakage flux circuit to become so located as that it will be ineffective on the armature; and thus I impose a limit 95 upon the torque exerted on the armature. In this way I am enabled to limit the series torque on the occurrence of heavy loads without reducing the sensitiveness of the instrument under light loads.

100 The term "armature" herein used means the element upon which the magnet field inductively acts to produce the desired result, and is not to be construed as limited to a fixed element or to a movable element, or to 105 an element of magnetic or to an element of non-magnetic material.

The invention is not to be construed as limited to a rigorous mathematical parallelism of the excess flux circuit 3 to the 110

plane of the armature face. The limiting cases are (1) for maximum torque, the axis of the flux circuit is at right angles to the plane of the armature; (2) for no torque, the axis of the flux circuit is parallel to the plane of the armature. Torque conditions between these limits will obviously depend upon the angle between the axis of the flux circuit and said armature plane.

10 I claim:

1. An electro-magnet, comprising a bifurcated core having end portions 1 of its arms parallel and at substantially right angles to the remaining portions 2 thereof, and series coils on said body portion, and an armature: the said body portion 2 of said core

being disposed substantially parallel to the plane of said armature.

2. An apparatus of the watt-meter type set forth, comprising a rotary armature, a bifurcated core having its end portions 1 in inductive proximity to a face of said armature and its body portion 2 disposed parallel to said face, and series coils on said body portion.

25 In testimony whereof I have affixed my signature in presence of two witnesses.

IRVING M. STEIN.

Witnesses:

GERTRUDE T. PORTER,
MAY T. McGARRY.
